CHARLES B. PIRIE, OF MCCOOK, NEBRASKA, ASSIGNOR OF ONE-HALF TO ALEXANDER C. PIRIE, OF WYMORE, NEBRASKA.

VALVE-GEAR.

1,074,520.

Specification of Letters Patent.

Patented Oct. 7, 1913.

Application filed March 7, 1912. Serial No. 682,171.

To all whom it may concern:

Be it known that I, CHARLES B. PIRIE, a citizen of the United States, and a resident of McCook, in the county of Redwillow and State of Nebraska, have invented a new and Improved Valve-Gear, of which the following is a full, clear, and exact description.

My invention relates to valve gears, and it has for its object to provide means for readily changing the lead of valve gears of the Walschaert type. As constructed, the combination lever is provided with a slot, in which slides a block connected with the valve stem, so that the combination lever may be raised by a link connected with an operating device in the engine cab for changing the lead of the engine.

Additional objects of the invention will appear in the following complete specification, in which the preferred form of the invention is disclosed.

In the drawings similar characters of reference indicate corresponding parts in all the views, in which—

25 Figure 1 is a view showing my invention as applied to a piston valve operated by the Walschaert gear; Fig. 2 is a transverse sectional view of Fig. 1; Fig. 3 is a diagrammatic view of the construction shown in Fig. 30 1 of the drawings; and Fig. 4 is a view showing my invention as applied to the slide valve operated by the Walschaert gear.

By referring to Fig. 1 of the drawings it will be seen that the Walschaert gearing is 26 of the usual type with the radius rod 5 provided with the block 6, which slides in the slot in the reverse link 7, a lifting link 8 being provided, connecting the radius rod 5 with the arm 9, the said arm 9 and an arm 10 being secured to the reverse shaft 11, the said arm 10 being connected by the reach rod 12 with the reverse lever 13. The reverse link 7 is connected by an eccentric rod 14 with the usual eccentric crank 15. The 40 forward end of the radius rod 5 is articulated to the combination lever 16, the lower terminal of this combination lever 16 being connected with the cross head arm 17 by a cross head link 18. The combination lever 16 has a slot 19, in which the block 20 is 45 adapted to slide; this block 20 is mounted on a wrist pin 21, connected with the arms 22, which are in turn secured to the rock shaft 23. The arms 24 are also secured to the rock shaft 23, and between these arms 24

there is articulated the link 25, which is connected with the valve stem 26. The shaft 27 is journaled in bearings 28 in the frame 29, and an arm 30 is secured to this shaft 27, the said arm 30 being connected with 60 the combination lever 16 by the lead link 31. In the cab of the locomotive there is journaled a screw 32, which is engaged by a threaded head 33, the threaded head 33 being connected with the arm 34, secured 65 to the shaft 27, by a rod 35.

It will be understood that while the valve gearing may operate in the well-known manner, the combination lever 16 may be raised as may be desired, by means of the 70 lead link 31, which is operated through the rod 35, the arms 30 and 34, and the shaft 27, by the screw 32 with the screw head 33, the screw being operated by the crank 36.

With my improvement the engineer may 75 quickly and conveniently change the lead of the engine, without getting out of the cab. This is a great improvement, for it has heretofore been necessary for a mechanic to work several hours on a valve gear of the 80 type described to change the lead.

In Fig. 4 of the drawings I have shown my invention as applied to a slide valve engine. With this construction the combination lever 16^a is provided with the slot 19^a, 85 the bottom of the combination lever 16^a being connected with the cross head arm 17^a, by a cross head link 18^a, the radius rod 5^a being articulated to the combination lever 16^a below the slot 19^a. Disposed for sliding 90 in the slot 19^a there is a block 20^a, in which there is a pin 37 this pin 37 being connected with the valve stem 26^a by members 38. With this form of the invention the combination lever 16^a is raised or lowered as 95 desired by the lead link 31 in any approved manner, as may be desired by the mechanism disclosed in Fig. 1 of the drawings.

It will be seen that the arc made by the lead link 31 when the combination lever 100 moves back and forth, will cause the combination lever to rise and fall during the stroke, allowing the steam to follow the piston an unusual distance with a given amount of lead, to cause a quick exhaust 105 opening and also retarding the closing of the exhaust port, thereby causing less compression in the cylinder. It will of course be understood that the combination lever 16 will be so supported by the lead link 31 110

when the lead link 31 is in normal position, as to obtain the best results with the particular engine to which my improvement is applied.

Having thus described my invention, I claim as new, and desire to secure by Letters Patent:

1. In a valve gear having reversing means, a combination lever having a slot, a valve stem, means slidably disposed in the slot for operating the valve stem, a radius rod articulated to the combination lever, means for operating the radius rod, a cross head link articulated to the combination lever and adapted to be articulated to a cross head arm, and means operable independently of the reversing means for moving the combination lever to change the lead.

2. In a valve gear, a combination lever, a valve stem, means by which the combination lever is adapted to operate the valve stem, a radius rod articulated to the combination lever, means for operating the radius rod, a cross head link articulated to the combination lever and adapted to be articulated to a cross head arm, and a link articulated to the combination lever for moving the combination lever independently of the means for operating the radius rod.

3. In a valve gear, a combination lever having a slot, a rock shaft, two arms secured to the rock shaft, a member mounted on one of the arms and slidably disposed in the slot in the combination lever, a valve stem articulated to the other arm on the rock shaft, a radius rod articulated to the combination lever, means for operating the radius rod, a cross head link articulated to the combination lever, and adapted to be articulated to a cross head arm, and a link articulated to the combination lever for moving the combination lever relatively to the means for operating the radius rod to change the lead.

4. In a valve gear, a combination lever having a slot, a valve stem, means slidably disposed in the slot for operating the valve stem, a radius rod articulated to the combination lever, means for operating the radius rod, a cross head link articulated to the combination lever and adapted to be articulated to a cross head arm, a rock shaft, two arms on the rock shaft, a link connecting one of the arms on the rock shaft with the combination lever, a screw, a screw member meshing with the screw, and a rod connecting the screw member with the other arm for moving the combination lever independently of the means for operating the radius rod.

5. In a valve gear, a combination lever, a valve stem, means connecting the valve stem with the combination lever, a radius rod articulated to the combination lever, means for operating the radius rod, a cross head link articulated to the cross head lever and

adapted to be articulated to a cross head arm, and a link articulated to the combination lever for moving the combination lever relatively to the means for operating the radius rod to change the lead.

6. In a valve gear, a combination lever, a valve stem, means connecting the valve stem with the combination lever, a reducing rod articulated to the combination lever, a reverse link connected with the reducing rod for operating the latter, a cross head link articulated to the cross head lever, and adapted to be articulated to a cross head arm, and a link articulated to the combination lever for moving the combination lever relatively to the connection between the reverse link and the radius rod to change the lead.

7. In a valve gear having reversing means, a combination lever, a valve stem, means having sliding engagement with the combination lever for operating the valve stem, a radius rod articulated to the combination lever, means for operating the radius rod, a cross head link articulated to the combination lever, and adapted to be articulated to a cross head arm, and means operable independently of the reversing means for moving the combination lever to change the lead.

8. In a valve gear, a combination lever, a valve stem, means having sliding engagement with the combination lever for operating the valve stem, a radius rod articulated to the combination lever, means for operating the radius rod, a cross head link articulated to the combination lever and adapted to be articulated to a cross head arm, a rock shaft, two arms on the rock shaft, a link connecting one of the arms on the rock shaft with the combination lever, a screw, a screw member meshing with the screw, and a rod connecting the screw member with the other arm for moving the combination lever independently of the means for operating the radius rod.

9. In a valve gear having reversing means, a combination lever, a valve stem, means having sliding engagement with the combination lever for operating the valve stem, a radius rod articulated to the combination lever, means for operating the radius rod, a cross head link articulated to the combination lever, and adapted to be articulated to a cross head arm, and a pivoted link articulated at a distance from its pivot to the combination lever.

10. In a valve gear having reversing means, a combination lever, a valve stem, means having sliding engagement with the combination lever for operating the valve stem, a radius rod articulated to the combination lever, means for operating the radius rod, a cross head link articulated to the combination lever, and adapted to be articulated to a cross head arm, a pivoted link ar- 130

ticulated at a distance from its pivot to the combination lever, and means operable independently of the reversing means for moving the link to change the lead.

5 11. In a valve gear, a radius rod member, means for operating the radius rod member, a valve stem member, means connecting the radius rod member with the valve stem member for operating the latter and for moving one of the members rela-

tively to the other and independently of the radius rod member, at the first means.

In testimony whereof I have signed my name to this specification in the presence of two subscribing witnesses.

CHARLES B. PIRIE.
